Section 1, Public Law 690, August 8, 1946
Patent expires March 14, 1964

1 Claim. (Cl. 158—73)

1

The present invention refers to an arrangement in oil burners of the type having a catching and collecting device provided in front of an atomizing nozzle for the fuel, by means of which catching device a controllable portion of the fuel jet is kept off the combustion zone outside the burner. In burners of this construction, the combustion air is generally conveyed in a tube surrounding the atomizing nozzle and the catching device. In order under all operating conditions to ensure the best possible fuel economy, the fuel quantity and the air quantity may suitably be controlled in a definite relationship, so that the air quantity is reduced simultaneously as the injected fuel quantity is reduced. At a low load, when the fuel and air quantities are small, the drawback is encountered, however, that the flame of the burner will be located immediately adjacent to the nozzle on account of the small air velocity. It may even occur that the flame will be located within the catching device, so that deposits will form in the latter, said deposits being apt even to clog the passages serving for carrying off the excess fuel.

The object of the invention is to eliminate this drawback and to provide an oil burner in which the combustion takes place well outside the catching device even at low loads.

According to the invention this and other objects are attained by the provision, in combination with the feature that the combustion air conveyed through a space provided radially outside the atomizing nozzle and the collecting means is controllable as to the quantity thereof in relation to the quantity of fuel supplied to the combustion zone, of a guiding means adapted in a manner known per se to catch a portion of the air flowing forth through said space, said guiding means being so constructed that the air flowing therethrough will be directed obliquely inwardly toward the longitudinal axis of the nozzle and away from the fuel nozzle.

The invention will be described more closely hereinafter with reference to an example of embodiment as illustrated in the accompanying drawing.

Fig. 1 shows the outer portion of an oil burner in longitudinal section, and Fig. 2 shows a longitudinal section through a complete burner unit.

1 designates a fuel nozzle having a variable spreading angle, if desired. Arranged about the fuel nozzle in a manner known per se is a rotary collecting drum 2. By displacing the nozzle 1 or by changing the spreading angle, the portion of the fuel discharged through the nozzle open-

2

ing 3 may be varied, while the quantity of fuel kept off the combustion zone is collected by the drum 2 and carried off through the opening 4 therein. The combustion air is conveyed in the space between the catching and collecting device 2 and the wall 5 of the burner housing. Provided outside the drum 2 is a tubular collecting member 6 of a curved or dish-shaped configuration in section, said member serving as a collecting and discharging bowl for the oil carried off the drum 2. Outside the member 6 there is provided a tubular guiding member 7 which is circular in cross section and which, together with the member 6, forms a guiding means for a certain portion of the combustion air. The guiding means formed by the members 6 and 7 is preferably nozzle-shaped in section, the same being thus restricted toward the outlet opening 8. Preferably, the nozzle is directed obliquely outwardly toward the centre line or axis of the mouth of the nozzle.

Arranged at the wall 5 are obliquely positioned guide blades 9, 10 to impart a rotary motion to the main body of the combustion air. The blades extend from the wall 5 inwardly to about the radial position of the edge of the guide member 7 directed against the direction of flow of the air. In the illustrated example, a ring of guide blades 9 is provided in front of the inlet opening of the guiding means, while a ring of guide blades 10 is provided behind said guiding means. The blades 9 and 10, or the latter at least, preferably have a small pitch, it being furthermore of advantage to arrange them so that they will together cover the radially outer portion of the air space, entirely or in part, and overlap one another.

The oil collected in the member 6 is carried off through a tube 11'. This tube may advantageously be given an oblong cross-section, and may be obliquely positioned in a manner such as to aid toward imparting a turbulent motion to the combustion air flowing outside the same.

The front edge of the member 6 is separated by a gap 12 from the part carrying the collecting drum 2, so that air may pass through the space between the parts 2 and 6 to prevent the production of a vacuum in this space during the operation, whereby the flame might be drawn rearwardly.

When the contrivance is adjusted for injection of a comparatively small quantity of fuel, a relatively small quantity of combustion air being consequently supplied, the guide blade rings 9 and 10 will have a braking effect on the air. The guide member 7 catches a comparatively large quantity of air, and this air is conveyed at

an increased velocity through the outwardly restricted nozzle directly toward the axis but at the same time obliquely outwardly from the nozzle opening 3. The ejected oil jet will thus have the necessary quantity of air supplied thereto at such a velocity and in such direction that the flame cannot strike into the burner. The guiding means also involves the advantage that the collecting member 6 is cooled by air, in operation.

Fig. 2 shows a complete burner unit provided with a burner according to Fig. 1. As will be seen from the figure, the nozzle 1 is arranged at the one end of a hollow, axially displaceable tubular member 11. The tubular member may be displaced to and fro with the aid of a hand lever 12 and levers 13, 14 and 15, among which the levers 14 and 15 are mounted on a pin 16, besides which the lever 15 is provided with a rounded end portion engaging into an annular slot 17 at the end of the member 11.

Liquid fuel is supplied to the nozzle 1 through the tubular member 11 by means of a pump arranged in a housing 18. The nozzle 1 is located in the interior of the rotatable drum 2 forming the catching device for a portion of the jet cone from the nozzle. The drum 2 is arranged on a hollow shaft 19 surrounding the member 11, and is rotatable relatively to the latter and mounted in a guide disk 20 within the casing 21 and in the rear wall 22 of the casing 21. Arranged on the casing 21 is an electric motor 23 adapted by means of wedge-shaped belts 24 to drive the hollow shaft 19, to which the fuel pump is coupled. Furthermore, the shaft 19 has a fan wheel 25 secured thereto and adapted to suck combustion air through openings 26 in the rear cylindrical portion of the casing 21 and to press such air into the furnace. Arranged in the cylindrical portion of the casing 21 is a controlling slide valve 27 for the combustion air. This slide valve, which is constituted by a body of revolution and situated coaxially with the fan wheel in front of the inlet thereof, may be adjusted axially by a rod 28 with the aid of a lever 29 operated by means of the hand lever 12. The openings 26 are tapering at the ends 30 thereof directed toward the fan wheel, so that the slide valve 27, when displaced to the right in Fig. 2 from the position shown, will initially reduce the air intake area comparatively slowly and then relatively more rapidly at the end of its displacement in said direction. By

shaping the openings 26 in a suitable manner and by a suitable association of the fuel control and the air control, it will be found possible to obtain an appropriate relationship between the air quantity and the fuel quantity at different loads.

What we claim is:

In an oil burner, a conduit for combustion air, a nozzle in said conduit for ejecting a spray of fuel oil, a tubular member surrounding said nozzle and spaced therefrom for catching and collecting part of the oil discharged from the nozzle, a hollow guide member outwardly and radially spaced from the tubular member and co-acting therewith to form a passage having an outlet portion extending obliquely toward the longitudinal axis of the nozzle, said passage receiving a minor part of the combustion air in said conduit and having a cross sectional area decreasing toward its outlet, the outer wall of said guide member and the inner wall of said conduit forming a second air passage through which a major part of the combustion air passes, and spaced slanting guide blades connected to the inner wall of said conduit and extending into said second passage to impart rotary motion to the combustion air passing therethrough.

BÖRJE KONRAD DANIELSSON.
